BINDER

Lester E. Shipman, Kew Gardens, N. Y.

Application December 1, 1932, Serial No. 645,158

6 Claims. (Cl. 129—41)

This invention relates to a binder especially one which is adapted to be used with loose leaves.

An object of the invention is to provide a simple and efficient means whereby the leaves can be quickly and easily assembled and fastened tightly in position between binding strips with a minimum of effort on the part of the operator.

A further object is to provide a connecting chain element extending between the binding strips which by reason of its nature can be flexibly adjusted to compress any reasonable amount of material between the strips.

A further object is to provide such a connection as can be employed to engage with suitable latching means to latch the binding strips to effect a compressing pressure on the embraced paper by the operation of suitable latches.

A further object is to provide a simple, inexpensive interconnected link chain capable of being twisted in one direction or another to change its effective length.

Further and more specific objects, features and advantages will more clearly appear from a consideration of the specification hereinafter when taken in connection with the accompanying drawing which forms part of the specification and which illustrates a present preferred form of the invention.

The invention in brief comprises a pair of binding strips between which loose leaves are to be compressed. One or more chains of interconnected links are anchored to one strip and extend through holes in the paper to the other strip. With a given number of leaves in position this chain can be twisted upon itself to adjust its effective length so that suitable latch members associated with its upper end may be operated to firmly compress the binding strips upon the embraced leaves. The chains are provided with simple needle-like threadable elements on their outer ends to facilitate the threading of the chains through the leaves. The loose ends of the chains after having been locked or latched are disposed in a trough-like casing either forming the upper binding strip or constituting part of said strip. This trough-like casing is preferably provided with a cover to contain and hold the loose ends concealed and out of the way while the binder is being used to prevent accidental unlatching. The preferred form of latch member comprises a slideable plate which is moved forward to slide beneath one of the links in the chain and exert an upward pressure on the link and pull the chain by frictionally pressing the binding strips more firmly on the leaves. Another form

of latch is an ordinary bar or pin which can be passed through the link just above the surface of the top strip enabling the chain to be twisted until sufficient pressure is exerted on the strip whereupon the ends of the pin can be locked in the lateral flanges of the trough-like casing. In this case also the free ends of the chain lie in the casing and are protected by the cover when not in use.

In the drawing which illustrates the present preferred form of the invention:—

Fig. 1 is a perspective view of the device;

Fig. 2 is a longitudinal vertical cross-section taken through part of the device;

Fig. 3 is a vertical transverse cross-section;

Fig. 4 is a detail of one of the latches;

Fig. 5 is a transverse section through the top binding strip; and

Fig. 6 is a partial perspective view of a modified form of latching means.

As shown in the drawing the invention is applicable to a book or loose-leaf ledger having a top 1, a bottom 2 and a flexible back 3. The top is provided with a binding strip 4 and the bottom is provided with a binding strip 5. These binding strips are preferably made of heavy leather, cardboard or may be made of metal, if desired.

Preferably on the top binding strip 4 there is disposed a trough-like metal plate 6 having longitudinally overturned flanges and over these is preferably disposed a cover plate 7 which may be pivoted thereto or may be slipped over the top of the trough plate by being snapped down over the same. The trough plate 6 is provided with suitable openings such as 8 therein which are to be disposed in alignment with suitable holes in the superposed leaves 9 of the book or ledger and are also in registration or alignment with suitable holes such as 10 in the bottom binding strip 5.

In order to hold the leaves tightly together a binding element such as a chain 11 extends upwardly through the aligned holes of the leaves 9. This chain at its bottom is provided with a cross bar 12 which is disposed transversely to the axis of the chain itself, and beneath the binding strip 5 to anchor the lower end of the chain in position. The chain 11 is designed to be in the form of interconnected, loosely connected links which are made merely by being interlinked and are not in any way positively connected by any such means as rivets or the like. Consequently this chain is exceedingly flexible in that its successive links can be turned in a direction at right angles

to its axis or twisted so as to considerably increase or decrease the effective length of the chain. The upper end of the chain is provided with a suitable bar-like threading member 13 to 5 enable the chain to be readily threaded upwardly through the leaves of the book.

After the chains of which there are at least two have been threaded the operator twists the chain somewhat to cause it to be pulled tight 10 and then slides the latch member 14 forward. This latch member comprises a plate having a central slot 15 and an upper sloping surface 16. The nearest link of the chain 11 is embraced by the slot 15 and the sloping surface 16 engages 15 beneath the link disposed next adjacent its top surface to exert an upward cam action on the chain and pull it tight and thus force the binding strips 4 and 5 firmly back on the embraced leaves 9. In order to retain the latch element 14 in 20 position the spring plate 17 is disposed beneath the path of travel of the cam latch to exert sufficient friction on its under portion to hold it in position. The lateral edges 18 and 19 of the cam latch element are adapted to lie in and 25 slide in the lateral flanges of the trough plate 6 and so that the latch element will be guided in its forward and backward movements. After the chains have thus been tightened and latched the remainder of the chain above the trough plates 30 6 is laid flat along it as shown in Figs. 1 and 2 and the cover 7 is then placed over the trough plate to keep these parts in position and to cover them.

In Fig. 6 a modified form of latch element 35 used with the general chain is shown which consists of a pin or bar 20 which is slid through that portion which lies just above the surface of the trough plate, and which is preferably twisted to twist the chain in order to create an inward pulling 40 action on the binding strips and, with this rigidity at a maximum, the pin is disposed as shown in Fig. 6 with its ends latched beneath the opposite flanges of the trough plate 6. The balance 45 of the chain, not shown in Fig. 6, may be disposed along the trough plate and covered, as previously described, if desired.

It will, therefore, be seen that this device includes a simple twistable interlinked chain anchored at one end and capable of being passed 50 through the holes in the paper and capable of being pulled to tighten the binding strips on the paper sufficiently. The character of the chain permits it being twisted to further effect tightening action. The provision of a simple threader 55 on the end of the chain facilitates the speed with which the device can be applied. The two forms disclosed for anchoring or latching the top of the chain are equally simple and effective. The 60 adjustable cover is also effective in preventing the loose ends of the chain from coming out and keeping the connecting devices covered so that there will not likely be any accidental unlatching during use.

65 It is further to be understood that in some forms of the invention, the chain instead of being definitely anchored at one end may be provided to engage with adjustable latches at both ends which would be merely a duplication of the construction shown. This would enable the chain to

be latched and released from either end as the circumstances might require.

While the invention has been described in detail and with respect to a present preferred form thereof it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

What is claimed is:

1. An improved binder which includes a binding strip, a trough-like casing associated therewith having laterally overturned longitudinal flanges, a cam-shaped latching element slidable along said trough and adapted to engage with a connector element to latch the same, and flexible spring means engaging the latch element to hold it in any desired adjusted position.

2. An improved binder which includes a binder strip having longitudinally laterally overturned flanges to form a trough, a slidable latch plate having outwardly extending flanges to slide beneath the lateral flanges of the strip, said latch plate having a sloping cam surface, a flexible strip disposed beneath the latch plate to engage it frictionally to hold it in a desired position, said sloping surface having a longitudinal slot to receive a portion of a connector to be latched, the sloping surface adapted to engage a part of said connector and latch the same to create a longitudinal tension therein.

3. An improved binder which comprises a trough-like binder strip, and an adjustable cover therefor, slidable cam latches disposed in said trough and adapted to engage with portions of a connector, the free ends of the connector adapted to lie in said trough and be housed beneath the cover.

4. An improved binder which includes a pair of spaced binder strips, a chain of loosely connected links fastened to one strip and passing through holes in leaves to and through the other strip, a slidable latch element moveable on said last mentioned strip, said latch having a slotted sloping cam surface adapted to engage a link of the chain as the latch is moved to exert a longitudinal pull on the chain.

5. An improved binder which includes a pair of spaced binder strips, a chain of loosely connected links fastened to one strip and passing through holes in leaves to and through the other strip, a slidable latch element moveable on said last mentioned strip, said latch having a slotted sloping cam surface adapted to engage a link of the chain as the latch is moved to exert a longitudinal pull on the chain, and friction means on the strip engaging the latch to hold it in adjusted position.

6. An improved binder which includes a pair of binder strips, a chain adapted to pass through leaves to be held, said chain anchored at the lower end to one of said strips, and a slidable latch moveable on the other strip to engage the upper end of the chain, said latch having a sloping slotted cam surface to engage with a link of the chain and exert a longitudinal pull on the chain.
